(21) Appl. No.: **29/272,856**

CLAIM

(22) Filed: **Feb. 20, 2007**

The ornamental design for an inverter with a charging capability, as shown.

(51) **LOC (8) Cl.** **13-02**

DESCRIPTION

(52) **U.S. Cl.** **D13/110**

FIG. 1 is a perspective view of an inverter with a charging capability showing my new design;

(58) **Field of Classification Search** D13/110,

FIG. 2 is a front view thereof;

D13/123, 184, 199; 307/150, 151; 337/186;

FIG. 3 is a rear view thereof;

361/600, 601, 730; 363/141, 142

FIG. 4 is a left side view thereof;

See application file for complete search history.

FIG. 5 is a right side view thereof;

D332,443 S * 1/1993 Sharpe D13/184

FIG. 6 is a top view thereof; and,

D413,567 S * 9/1999 Person et al. D13/110

FIG. 7 is a bottom view thereof.

5,949,640 A * 9/1999 Cameron et al. 361/600
